United States Patent Office

Des. 202,304
Patented Sept. 14, 1965

202,304

CARRIER TOP FOR BOTTLES OR SIMILAR ARTICLE

Glenn E. Struble, Hamilton, Ohio, assignor to Diamond International Corporation, a corporation of Delaware

Filed Oct. 23, 1964, Ser. No. 82,293

Term of patent 14 years

(Cl. D58—26)

FIG. 1

FIG. 2

FIG. 3

FIG. 4

FIG. 1 is a perspective view of a carrier top for bottles or similar article, showing my new design;

FIG. 2 is a top plan view thereof;

FIG. 3 is a side elevational view thereof; and

FIG. 4 is an end elevational view thereof.

The broken line showing of a bottom portion of a carrier in FIG. 1 is for illustrative purposes only.

I claim:

The ornamental design for a carrier top for bottles or similar article, as shown and described.
